UNITED STATES PATENT OFFICE

140,190

DESIGN FOR A CLIP FOR FASTENING INSULATING MATERIALS TO WALLS AND CEILINGS

Oliver C. Eckel, Cambridge, Mass.

Application May 27, 1944, Serial No. 113,769

Term of patent 14 years

(Cl. D54—9)

To all whom it may concern:

Be it known that I, Oliver C. Eckel, a citizen of the United States, residing at Cambridge, in the county of Middlesex, in the Commonwealth of Massachusetts, have invented a new, original, and ornamental Design for a Clip for Fastening Insulating Materials to Walls and Ceilings, of which the following is a specification, reference being had to the accompanying drawing, forming a part thereof, in which:

Figure 1 is a perspective view of a clip for fastening insulating materials to walls and ceilings embodying my new design, Figure 2 is a front elevational view thereof and Figure 3 is a sectional view taken on the line 3—3 of Figure 2.

I claim:

The ornamental design for a clip for fastening insulating materials to walls and ceilings, substantially as shown.

OLIVER C. ECKEL.
